Primary Examiner — Karen S Acker*Assistant Examiner* — Wendy Arminio(74) *Attorney, Agent, or Firm* — Abbey A. Lopez; Amy I. Ahn-Roll(57) **CLAIM**

The ornamental design for a package for wax articles, as shown and described.

DESCRIPTION

FIG. 1 is a back perspective view of a package for wax articles;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines shown in the drawings depict portions of the package for wax articles that form no part of the claimed design.

1 Claim, 5 Drawing Sheets(56)
